ATTORNEYS

UNITED STATES PATENT OFFICE.

EMIL KLAHN, OF JERSEY CITY, NEW JERSEY, ASSIGNOR TO THE KEYSTONE WATCH CASE COMPANY, OF PHILADELPHIA, PENNSYLVANIA.

WATCH-BOW FASTENER.

SPECIFICATION forming part of Letters Patent No. 449,255, dated March 31, 1891.

Application filed January 2, 1891. Serial No. 376,536. (No model.)

To all whom it may concern:

Be it known that I, EMIL KLAHN, a citizen of the United States, and a resident of Jersey City Heights, in the county of Hudson and 5 State of New Jersey, have invented certain new and useful Improvements in Devices for Fastening Watch-Bows, of which the following is a specification.

My invention relates to an improved bow- 10 fastening device for watch-cases; and it consists of certain improvements which are fully set forth and described hereinafter, and which are shown in the accompanying drawings.

In carrying out my invention I employ a 15 watch-case pendant provided with holes or apertures and a bow having its ends, which are inserted in these apertures of the pendant, provided with locking-heads, which are journaled in an eccentric position upon the 20 ends of the bow. When the bow ends are inserted in the apertures, these heads are turned so as not to prevent the passage of the bow ends through the apertures, and are then turned out so as to project over 25 the apertures upon the inside of the pendant, and thus lock the bow ends in place. These heads may be carried upon pins or screws passing through the ends of the bow, as is hereinafter set forth.

30 In the drawings, Figure 1 represents a front view of a watch-pendant with a bow attached to the same by means of my improved fastening device, and Fig. 2 shows the pendant in vertical section and the bow partially in section.

Similar letters of reference indicate corresponding parts.

A in the drawings represents a watch, the pendant B of which is provided with two 40 holes or apertures *b b*, diametrically opposite each other. The bow C is of an annular shape with a part cut out, as usual. The so-formed ends of the bow are provided with screw-holes terminating in the flat surfaces of the 45 ends.

D are screws or pins having eccentric-heads *d d*, which are screwed or pushed into the holes of the bow ends, so that the eccentric-heads are in face with the flat surfaces 50 of the bow ends.

The bow is fastened to the pendant in the following manner: The screws or pins D are screwed or pushed through the holes of the bow ends until both eccentric-heads of the same come in contact, or nearly so, with the 55 surfaces of the ends and without projecting beyond the ends laterally, as shown at the left-hand side of Fig. 2. The ends of the bow are then bent apart, so that they can pass over the surface of the watch-pendant, and 60 are pressed into the holes of the said pendant. When this has been done, the eccentric-heads *d d* are turned until they have such a position that they overlap the lower borders of the holes *b* in the pendant B, as shown at 65 the right-hand side of Fig. 2. The bow is thus kept in a reliable position on the pendant as the heads press against the inner surfaces of the pendant and do not allow the bow to be removed therefrom unless the heads 70 *d d* are turned back so that they do not project laterally beyond the ends of the bow. When turned into position for locking the bow in place, the pins or screws may be soldered to the bow or otherwise secured against 75 movement.

The free ends of the screws or pins may be cut off and provided with notches, as shown in Fig. 1, so that they can be turned by means of a screw-driver when it shall be necessary 80 to put the heads inside of the pendant into another position.

The chief feature of the invention consists of the heads *d d*, journaled eccentrically upon the ends of the bow, so that they may be 85 turned so as not to project laterally when the bow ends are inserted, but may be turned out when the bow is in place, so as to project over the apertures of the pendant on the inside, and thus lock the bow ends in place. 90

Having now described my invention, what I claim as new, and desire to secure by Letters Patent, is—

1. A device for fastening watch-bows, consisting of a hollow pendant of a watch-case 95 with two holes, a bow having screw-holes terminating in the surfaces of its ends, and screws or pins with eccentric-heads screwed or pushed into the holes of the bow, which heads, when turned, press against the inner 100

borders of the holes in the neck, substantially as and for the purpose specified.

2. In a watch-bow fastener, the combination, with the pendant, of a watch-case having apertures upon opposite sides, a bow, and heads journaled in an eccentric position upon the ends of said bow, adapted to be turned, when the bow ends are inserted in the apertures of the pendant, so as to project beyond

said apertures on the inside, substantially as to and for the purpose specified.

Signed at New York, in the county of New York and State of New York, this 22d day of November, A. D. 1890.

EMIL KLAHN.
